CLAIM

The ornamental design for the lens for lights, as shown and described.

DESCRIPTION

FIG. 1 is a perspective top side view of the lens of the present invention.

FIG. 2 is a top side view of the lens.

FIG. 3 is a bottom side view of the lens.

FIG. 4 is a front side view of the lens.

FIG. 5 is a back side view of the lens.

FIG. 6 is right side view of the lens; and,

FIG. 7 is a left side view of the lens.

The broken line portions of the lens for lights are included for the purpose of illustrating the environment in which the claimed design may be used and form no part of the claimed design.
